UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

POURING POT FOR FEEDERS AND INGOT MOLDS.

Application filed December 8, 1923. Serial No. 678,379.

To all whom it may concern:

Be it known that we, BLOOMFIELD H. HOWARD, of Washington, District of Columbia, and ERNEST J. TURNER, of Pittsburgh, 5 in the county of Allegheny and State of Pennsylvania, citizens of the United States, have invented new and useful Improvements in Pouring Pots for Feeders and Ingot Molds, of which the following is a specification, reference being had therein to the accompanying drawings.

Our invention relates to improvements in pouring pots for feeders and ingot molds.

The object of our invention is to provide 15 a pouring pot adapted to be removably supported by a feeder supported by the upper end of the mold or supported directly upon the upper end of the mold, and so constructed and arranged that it can be used 20 more than once in the pouring operation of filling the mold with molten metal.

Another object of our invention is to provide a pouring pot of this character which will function with our feeders in preventing 25 seams and holes known as piping and also reduce "segregation" to a minimum.

Another object of our invention is to provide a simple, cheap and effective pouring pot, adapted to be used in conjunction with 30 feeders and molds of different character, having certain details of structure and combination of parts, hereinafter set forth.

In the accompanying drawings; Figure 1 is a perspective view of an ingot 35 mold showing the pouring pot applied to a feeder constructed under Patent No. 1,211, 899 patented January 9, 1917.

Figure 2 is a vertical transverse sectional view of Figure 1.

Figure 3 is a vertical transverse sectional view similar to Figure 1 showing a modified form of pouring pot.

Figure 4 is a vertical transverse sectional view showing a still further modified form.

Figure 5 is a vertical sectional view of another modified form of pouring pot.

Figure 6 is a vertical sectional view of a still further form of modified form of pouring pot.

Figure 7 is a transverse sectional view taken on the line 7—7 of Figure 6.

Figure 8 is a vertical transverse sectional view partly broken away showing three modified forms of pouring plates capable of being used in the bottom of the pouring pot.

Figure 9 is a perspective modified form of the pouring plate adapted to be used in either of the forms shown in Figures 2 and 3.

Referring now to the drawings, 1 represents the ingot mold having the usual bore 2 therethrough, which as shown gradually increases in diameter towards its lower end but which can be of any desired form as shown in our numerous patents, as the form mold, forms no part of our invention. Supported within the upper end of the bore of the ingot mold is the feeder 3 which is provided on its outer periphery with longitudinal extending ribs 4 the lower ends of which are to rest upon the upper ends of the ingot mold and support the feeder within the bore of the mold. In Figures 1, 2 and 3 of the drawings instead of having the ribs resting directly upon the upper edge of the mold, 75 we have shown bricks 5 placed between the lower ends of the ribs 4 and the upper end of the mold.

Our improved pouring pot consists of a metal receptacle 6 having an external bore 80 equal to the internal bore of the feeder 3 and provided at its upper end with the annular flange 7 adapted to rest on the upper edge of the feeder 3. The flange 7 is provided with loops or hooks 8 by means of which the pot is handled in any desired manner. As shown in Figure 2 of the drawings, the lower end of the pot 6 is provided with an inwardly extending flange 9, leaving the central opening 10 in the lower end of the 90 pouring pot.

The pot 6 is lined with fire brick 11 which rests upon the flange 9 and said flange extending inwardly beyond the fire brick 11 and loosely fitting in the lower end of the pot and resting upon the flange 9 is the feeder plate 12 which closely fits against the fire brick lining 11. This feeder plate is provided with a series of openings 13 extending vertically through and, through which the molten metal passes into the mold. There may be any desired number of these openings as it has been found that by pouring the metal in small streams a perfect ingot 100 is formed.

In the modification shown in Figure 3 of the drawings the pouring pot 6 has a solid bottom 14 provided with openings 15 adapted to register with the openings 13 in the pouring plate. In this modified form 110

the pouring pot, fire brick are constructed and arranged exactly the same as that shown in Figure 2 of the drawings.

In the modification shown in Figure 4 of the drawings, the feeder 3 has the ribs 4 resting directly upon the upper edge of the ingot mold 1. In this form the pouring pot 6 has a rounded lower end 16 provided with a series of openings 17 and resting in the lower rounded end of the pouring pot is the feeder plate 18 having opening 19 corresponding with the opening 17. In this form the fire brick 20 rests on and is supported by the upper edge of the feeder plate 18.

In Figure 5 of the feeder 3 is arranged exactly the same, and the pouring pot 6 has its lower end tapering in all directions. These four tapering walls are provided with openings 22 and resting within the lower end of the pouring pot is the pouring plate 23 having its four walls tapering corresponding with that of the pouring pot, and provided with opening 24 registering with the opening 22.

In Figure 6 of the drawings the feeder 4 is arranged precisely the same as that shown in Figures 4 and 5 and the lower end of the pouring pot has two obliquely arranged walls 26 and 27 provided with opening 28 and arranged in the lower end of the pouring pot are two pouring plates 29 and 30 meeting at the point 31 as shown in Figure 7. The end walls of the bottom are covered by the bricks 31 as shown in Figure 6, and the fire brick lining 32 rests upon the upper end of the pouring plates 29 and 30 and the brick 31.

In Figure 8 the feeder 3, pouring plate 6 have fire brick 11 well constructed and arranged precisely like that shown in Figure 2 of the drawings, instead of having the flat pouring plate 10, we have shown the semi-circular pouring plate 33 having the opening 34 arranged therein. In this

figure two modified forms of the pouring plates are shown as indicated at 34 and 35.

In Figure 9 the pouring plate 10 such as shown in Figure 2 of the drawings could be provided with elongated slots 36 instead of the opening 13. The same principle could be employed in any of the other ones shown.

Having thus fully described our invention what we claim and desire by Letters Patent is;

1. A pouring pot comprising a metallic body portion having an annular flange at its lower end to support a refractory lining and pouring plate.

2. A pouring pot comprising a metallic body portion having an outwardly extending supporting flange at its upper end, an inwardly extending flange at its lower end adapted to support a refractory lining.

3. In combination with an ingot mold and a feeder supported within the upper end of the mold, of a pouring pot resting upon the upper end of the feeder and extending into the feeder, a removable pouring plate in the lower end of the pot, and having a series of openings therein.

4. In combination with an ingot mold and a feeder supported within the upper end of the mold of a pouring pot supported by the upper end of the feeder and having a fire brick lining provided with a series of openings at its lower end.

5. In combination with an ingot mold having a feeder extending into the mold and supported thereby of a pouring pot having a lateral projection at its upper end resting upon the upper end of the feeder, and a fire brick lining in the pot having a series of small pouring openings at its lower end.

In testimony whereof, we have signed this specification.

BLOOMFIELD H. HOWARD.
ERNEST J. TURNER.
